UNITED STATES PATENT OFFICE

MARC BIRKIGT, OF BOIS-COLOMBES, FRANCE

SAFETY HEATING DEVICE

Application filed September 19, 1927, Serial No. 220,558, and in Belgium June 23, 1927.

The present invention relates to safety heating systems for inflammable materials and more particularly to systems for the safe utilization of the exhaust gases of internal 5 combustion engines in the heating of carburetors.

One of the objects of the invention is to provide a special exhaust conduit formed so that, in the event of its breakage, there 10 is no danger of igniting the explosive vapors in the vicinity of the carburetor.

Another object is to provide means for cooling the exhaust gases before their passage into the jacketed carburetor or similar 15 heat exchange device so that their temperature is insufficient to ignite any explosive mixture with which they may accidentally come into contact.

Further objects will appear in the course 20 of the detailed description which will now be given with reference to the accompanying drawings, in which:

Fig. 1 is a partial vertical section through 25 an internal combustion engine fitted with one form of a safety device constructed in accordance with the invention;

Fig. 2 is an elevation of the assembly represented in Fig. 1;

Fig. 3 is a section taken on line 2—2 of 30 Fig. 1; and

Fig. 4 is a section similar to Fig. 3 of a second form of safety device.

Referring to the various figures of the drawing, there is shown a cylinder block, 35 which may be of any convenient design, fitted with an exhaust conduit *g*. A by-pass collar *a* is interposed between the cylinder block and conduit *g*, and communicates with an expansion chamber *b* of sufficient size to cool 40 the exhaust gases passing therethrough to a sufficiently low temperature to prevent ignition of an explosive mixture. The partially cooled exhaust gases then pass through a conduit *c* leading to a heating packet *d* enclosing the whole or part of a carburetor *e*.

Chamber *b* may be conveniently formed of 50 an annular offset *f* integral with exhaust conduit *g* and embracing by-pass collar *a*, and may be held in position by any conven-

ient form of joint uniting it with cylinder block *h*.

Communication between chamber *b* and the inside of the exhaust conduit is established by means of a plurality of perforations 55 passing through collar *a* and grouped together, preferably, diametrically opposite outlet *i* leading to conduit *c*. These perforations serve not only as a means of communication but also function similarly to the wire-gauze in a Davy safety-lamp to prevent the 60 passage of flames from the inside of the exhaust conduit to chamber *b*.

When annular wall *f* is to be connected to block *h* by means of bolts, spacing tubes may 65 be arranged inside chamber *b* to prevent buckling of walls *f* when the bolts are tightened.

If desired, collar *a* may be reinforced by 70 a ring *j* provided with perforations *a*¹ serving to more thoroughly insure against danger of explosion.

In the event of the rupture of tube *c* from 75 any cause, the gases traversing the perforations of collar *a* will be prevented (1) by the "Davy" effect of the latter and (2) by the cooling effect of expansion chamber *b* from igniting explosive vapors in the vicinity of the motor and, more particularly, those surrounding carburetor *e*.

What I claim is:—

1. In an internal combustion engine, a safety heating system comprising a cylindrical exhaust conduit having a plurality of perforations grouped on part of a circumference thereof, an expansion chamber enclosing that part of the cylindrical exhaust conduit having perforations therethrough, a conduit communicating with said expansion chamber at a point removed from 85 said perforations, and jacketed fuel supply means connected to said last named conduit.

2. In an internal combustion engine, a cylinder block, a jacketed carburetor, an exhaust conduit having a by-pass orifice formed 90 therein adapted to conduct part of the exhaust gases toward said jacketed carburetor, a by-pass conduit extending from the jacketed carburetor to a point adjacent said by-pass orifice, and an expansion chamber in- 95 100

terposed between said by-pass orifice and the entrance to said by-pass conduit, said expansion chamber being dimensioned so as to cool the by-passed exhaust gases to a temperature below the ignition temperature of the fuel vapors in the vicinity of the cylinder block prior to their entrance into the by-pass conduit, whereby, in case of rupture of the latter, fire is prevented.

10 In testimony whereof I have hereunto set my hand.

MARC BIRKIGT.
